(57) **CLAIM**

The ornamental design for a wind powered generator, as shown and described.

DESCRIPTION

FIG. 1 is a front view of a wind powered generator showing my new design;

FIG. 2 is a rear view of the wind powered generator;

FIG. 3 is a right side view of the wind powered generator;

FIG. 4 is a left side view of the wind powered generator;

FIG. 5 is a top view of the wind powered generator;

FIG. 6 is a bottom view of the wind powered generator; and,

FIG. 7 is a top front side perspective view of the wind powered generator.
